UNITED STATES PATENT OFFICE.

LIONEL NELSON, OF WELLINGTON, NEW ZEALAND.

GAS PRODUCER.

1,408,465.

Specification of Letters Patent.

Patented Mar. 7, 1922.

Application filed November 15, 1917. Serial No. 202,132.

To all whom it may concern:

Be it known that LIONEL NELSON, citizen of the British Empire, residing at Karori, city of Wellington, Dominion of New Zealand, has invented certain new and useful Improvements in Gas Producers, of which the following is a specification.

This invention is for a method of and apparatus for producing gas for internal combustion engines and like purposes and the object of the invention is to convert the constituents of wood, wood shavings and the like without first converting same into charcoal—and of bituminous non-caking coal and 15 of fuel such as lignite peat and the like, into a clean enriched gas free from tarry impurities suitable for the above purposes. The invention consists in the features and combinations and arrangements of parts 20 hereinafter described and more particularly set forth in the claims.

The object of the invention is effected by arranging wood or non-caking coal or fuel such as lignite peat and the like in lumps or 25 pieces so that there are air spaces between the lumps or pieces, supplying where necessary the requisite quantity of moisture (either water or steam), feeding the fuel through the top of a preferably oblong or 30 oval generator effectually removing the ashes and drawing the gas down by suction through the grate of the generator so that the tarry products are consumed and partly used in enriching the gas produced.

35 In the accompanying drawings illustrating the invention,

Fig. 1 is a sectional view taken approximately on the line D—D of Fig. 3;

Fig. 2 is a horizontal sectional view of 40 Fig. 1;

Fig. 3 is a front view of a gas producer plant constructed in accordance with the present invention; and

Fig. 4 is a plan view thereof.

45 The gas producer plant according to this invention is hereinafter described especially for use on small launches with ordinary marine type petrol motors of suitable makes but it can also be used with ordinary gas engines and either on land or on a boat. It 50 comprises a rectangular shell which contains integrally the generator 1, and the scrubber or scrubbers 25 and so economizes space. The generator is a fire brick lined compartment, having inspection doors 26, fire doors 55 27 and cleaning doors 28. The grate 8 situ-

ated in the bottom part of the generator 1 is supported by lugs 29 riveted to the sides of the generator shell. To keep the fuel clear of ash and clinker the fire grate 8 is rocked 60 to and fro on lugs 29 by means of an agitator connected to the grate 8 at one end and to a lever 30 at the other, a gland 31 (Fig. 3) on the generator 1 shell preventing the admission of air. The scrubber 25 is a rectangular compartment separated from the generator by a partition plate 32. This plate 32 is gas-tight at the top and both sides, but has an opening 33 at the bottom to allow the gas to be drawn through the 70 grate 8 under the partition 32 and up through porous material 34 such as coke, broken bricks or tiles, or pumice in the scrubber 25 the porous material being supported by a grid 35.

75 Where two or more compartments are provided for the scrubber they are separated by partition plates such as 36 open at top or bottom as required to allow the gas to flow up one and down the next or vice versa. 80 The scrubber owing to the comparative cleanliness of the gas supplied from the generator acts mainly as a cooler as well as a washer. An overflow pipe 37 connects the scrubber 25 with the water seal ashpit 38. 85 Fresh or salt water is connected to the sprayer 39 which is continually spraying the porous material through which the hot gases flow, the water flowing into the water-sealed ashpit 38.

90 An overflow 40 prevents the water in the ashpit from rising too high and the ashpit is further sealed by means of a seal plate 41 which is secured in position or removed at short notice by means of dogs, not shown.

95 On the top plate 42 of the generator 1 is situated a feeding hopper 43 damper slide 44 vent pipe 45 and test cock 46. A hand starting fan 47 (Figs. 1 and 3) is connected to the top of the front plate of the generator shell.

100 The scrubber 25 is connected to an engine, not shown, by means of an outlet pipe 48 which is connected by means of an atmospheric cock 49 and connecting pipes to the 105 vent pipe 45. Separate top plates 42 and 50 are provided for both the generator 1 and scrubbers 25.

110 Cleaning doors 51 are provided on the scrubbers for the purpose of cleaning or emptying them. The distillation zone 17, the combustion zone 18, the decomposition

zone 19 and the ash zone 20 are shown approximately in their relative positions.

- In the operation of the device, before starting up a new plant fill the ashpit 38 with water to the level of the overflow 40. Open the damper slide 44 in the flange of the vent pipe 45. Next place paper, shavings, short sticks and the like on grate and set alight. This should be done through the door 27 and the door 28 should also be open for a while to allow sufficient draught to ensure quick combustion. The bricks in these doors are left loose but after the fire is well alight, should be carefully replaced in position. The generator should next be gradually filled up with short pieces of hard wood until half full of ash and charcoal, it should then be filled up with whatever fuel is to be used in the manner hereinbefore described.
- After burning for another half or three-quarters of an hour the plant is ready for work. To raise gas proceed as follows:— See that the generator is full of fuel and turn on scrubber water from sprayer 39. Shut the damper slide 44, open atmospheric cock 49 and operate fan 47 which forces air into and down through the incandescent fuel in generator. The resultant gas passes through the grate 8 and thence through the scrubber and atmospheric cock 49 and vent pipe 45 to the atmosphere. When sufficient air has been thus supplied to raise the incandescent fuel to the required temperature to generate gas (which is ascertained by testing the gas at the test cock 46) the engine should be started on benzine and run for a few minutes till warmed up, then changed over to gas. Close atmospheric cock 49 before changing over, and change over each cylinder separately. During running it is better to fire the generator lightly and often, rather than to supply considerable quantities of fuel at long intervals. Uniformity of size of fuel makes for greater efficiency. The correct intervals for charging generator will depend on the amount of gas drawn off from the producer, but once each half hour is a good average. A water gauge glass (not shown) is provided to show the amount of suction on the generator. The fluctuation on this gauge should never exceed six inches.
- When this limit is reached it shows that ashes are accumulating in the generator and obstructing the free passage of the gas. When this occurs the grate agitator should be given a few sharp shakes causing the ashes to fall through the grate 8 into the ashpit 38, these ashes should be removed as often as is necessary. See that the water in ashpit does not rise above overflow, owing to stoppage of pipes, failure of pump and the like. This is important. If the water in the seal ashpit rises too high it may result in putting the fire out. The seal plate 41 is used in the event of rough weather to further seal the ashpit. When shutting down see that the generator is full of fuel, adjust damper slide 44 to give the correct amount of draught and shut off scrubber water, then stop engine. Leave the inspection doors 26 off the faces about an eighth of an inch to admit the air necessary to keep the plant alight whilst standing idle. Experience will show how much it is necessary to leave open the damper slide 44 and also if more air is necessary through the inspection doors 26. When starting up from banked fires before commencing to oil engine open the doors 27 and 28, also damper slide 44 to allow the fire to draw up well. When ready to generate gas, shut these and open atmospheric cock 44 and proceed in the same manner as described for raising gas.
- I claim—
- In a gas producer, a shell, a partition separating said shell into a pair of communicating compartments, a generator in one compartment and a scrubber in the other, a vent pipe communicating with the generator, a pipe communicating with the scrubber and with said vent pipe, means for cutting off direct communication between the generator and vent pipe, and means for causing gas to flow from said generator through the scrubber and thence to the vent pipe.
- In testimony whereof I have hereunto set my hand in presence of two subscribing witnesses.

LIONEL NELSON.

Witnesses:

ANDREW JOHN PARK,
GRACE SHELDRAKE.
